UNITED STATES PATENT OFFICE.

ALBERT RAMMOSER, OF BERLIN, GERMANY.

WASHING-MACHINE.

SPECIFICATION forming part of Letters Patent No. 409,501, dated August 20, 1889.

Application filed August 1, 1888. Serial No. 281,697. (No model.) Patented in Germany July 26, 1887, No. 42,550; in England May 23, 1888, No. 7,584; in France June 2, 1888, No. 185,152, and in Austria-Hungary September 22, 1888, No. 28,063 and No. 26,821.

To all whom it may concern:

Be it known that I, ALBERT RAMMOSER, a subject of the King of Prussia, Emperor of Germany, residing at the city of Berlin, in the 5 Kingdom of Prussia, Empire of Germany, have invented certain new and useful Improvements in Washing-Machines, (for which I have obtained a patent in Germany, No. 42,550, dated July 26, 1887; in France, No. 185,152, 10 dated June 2, 1888; in England, No. 7,584, dated May 23, 1888, and in Austria-Hungary, No. 28,063 and No. 26,821, dated September 22, 1888,) of which the following is a specification.

15 This invention relates to a washing-machine in which the clothes to be washed are laid upon a cloth or apron provided with transverse slats, and are operated upon by a roller having its surface provided with longitudinal slats or ribs.

The invention will be understood on reference to the accompanying drawings, which represent three modifications in the construction of the machine.

20 Figure 1 is a longitudinal vertical section, and Fig. 2 a transverse vertical section, of the first modification. Fig. 3 is a longitudinal vertical section, and Fig. 4 a transverse vertical section, of the second modification. Fig. 30 5 is a vertical section, and Fig. 6 a top view, of the third modification. Fig. 7 is a vertical sectional view of a portion of Fig. 3.

In Figs. 1 and 2, A represents a water-tight tank or tub, in which is suspended a sacking 35 or apron B, having its ends attached to the inner sides of the two opposite ends of the tub, near the top thereof, so that the intermediate portion will sag down nearly to the bottom of the tub. The apron B is composed 40 of flexible bands or straps b, having attached thereto the slats or ribs a, which are of triangular form in their cross-section. Between the slats a and the straps b there may be interposed a sheet of network or of perforated 45 india-rubber cloth.

The tub A is provided with a removable cover G, in the center of the upper side of which is a standard g, in which is pivoted an oscillating beam E, provided with a rigidly-50 attached handle or lever E'.

To the ends of the beam E are attached bars e e', to the ends of which are pivoted the upper ends of rods F F'. These rods pass between pairs of friction-rollers f, through the cover G, and into the tub A above the apron B, and at their lower ends are journaled rollers D D', which have their surfaces provided with longitudinal slats or ribs, or, in lieu thereof, their surfaces may be grooved or fluted.

55 At about the center of the interior of the tub A, under the apron B, a smooth roller C is journaled in elastic bearings, each of which consists of a block g' on the upper end of a shank g², working in lugs g³ on a plate secured to the side of the tub, with a spring d surrounding the shank between the block and the uppermost lug, so that said roller C is free 60 to yield to any unusual pressure which may be brought to bear upon it.

7c The operation is as follows: The tub A being supplied with the proper quantity of water, the clothes to be washed are spread on the ribbed or slatted apron B, with sufficient water in the tub to cover them. Supposing 75 the parts to be in the position shown in Fig. 1—that is to say, with a portion of the apron nearly straight between the roller C and one end of the tub and the other portion of the apron between said roller and the opposite 80 end of the tub sagged down nearly to the bottom of the tub, in which case the roller D is in the lowest portion of the apron and the roller D' is above the nearly straight portion.

85 When the handle E' is moved toward the right-hand side of the drawings, the positions of the parts will be reversed, the roller D and the sagged portion of the apron rise, and the roller D' and the nearly straight portion of the apron descend until they are as low as 90 the opposite portion was previously. By means of this reciprocating vertical motion and the rotary motion of the rollers the clothes are thoroughly rubbed together and kneaded between the rollers and the apron 95 and brought into contact with different portions of the water in the tub, as their positions are constantly changed. If the thickness of the layer of clothes should be too great, the elastically-journaled roller C will 100

yield to the pressure, and thereby prevent the clothes from being torn. The tub is provided with a faucet f^2 for drawing off the water.

5 In the modification shown in Figs. 3 and 4 the oscillating beam and the bars and rods are dispensed with and the rollers D^2 are weighted and operate by their own gravity. The central roller C^2 has its periphery provided with ribs d^2 , which engage with the under side of the apron B in the intervals between the ribs on said apron, Fig. 7. One end of the shaft of the roller C^2 is provided with a pinion R, which is engaged by a toothed segment Q, pivoted on the side of the tub, and provided with a handle E^2 for oscillating it. When the handle is oscillated in either direction, a reciprocating rotary motion is imparted to the central roller C^2 , which in turn imparts a reciprocating curvilinear motion to the apron B, causing it to alternately straighten out between the roller C^2 and one side of the tub, and sag down between said roller and the opposite side of the tub, during which movements the rubbing-rollers D^2 are kept in contact with the clothes and the apron by their own gravity and rotate on their own axes, rising and lowering with the contiguous portions of the apron and the clothes, and rubbing the clothes between themselves and the apron as they so rotate and rise and fall. When at their highest position, the rollers are prevented from rolling off the apron by means of partitions L, extending downward from the lid or cover G.

10 In the modification shown in Figs. 5 and 6 the apron B has its ends attached to two rollers H, journaled in the sides of the tub at opposite ends near the top, with the intermediate portion of the apron sagged down into the tub, and carrying a weighted ribbed rubbing-roller D^3 in the sagged portion. The shafts of the rollers H carry toothed or sprocket

wheels or pulleys K, around which passes an endless chain or belt J. One of the shafts 45 also carries a pinion M, which is engaged by a pivoted toothed segment Q ^{3} , provided with a handle E^3 , for oscillating it. When the handle E^3 is oscillated in either direction, an intermittent curvilinear motion is imparted to 50 the apron, so that its ends are alternately wound around one of the rollers and unwound from the other, while the weighted roller D^3 remains in the sag near the bottom of the tub, where it rotates on its own axis, pressing 55 and rubbing the clothes between itself and the apron in substantially the same manner as above described.

What I claim as new, and desire to secure by Letters Patent, is—

60 1. A washing-machine consisting of a tub and a flexible slatted or ribbed apron having its ends secured within the tub and forming a sag, and a weighted automatically-rotating ribbed roller working in the sag of the 65 apron, substantially as set forth.

2. A washing-machine provided with a flexible slatted or ribbed apron having its ends fastened to two rollers journaled at two opposite sides of the tub and provided with 70 means for reciprocally rotating them, and with a weighted automatically-rotating ribbed roller working in the sag of the apron in the tub, whereby provision is made for washing the clothes between said apron and roller by 75 the reciprocating curvilinear motion of the apron and the reciprocating rotary motion of the weighted roller, substantially as herein described.

In testimony whereof I have signed my name 80 to this specification in the presence of two subscribing witnesses.

ALBERT RAMMOSER.
